The ornamental design for a display screen of a medical pump with a graphical user interface, as shown and described.

References Cited

DESCRIPTION

U.S. PATENT DOCUMENTS

The FIGURE is a front view of display screen of a medical pump with a graphical user interface, showing the new design.

D65,832 S 10/1924 Remark
D76,595 S 10/1928 Balzer
D89,168 S 2/1933 Carlson
D107,079 S 11/1937 Hedfield et al.
D263,997 S 4/1982 Preussner

The ornamental design which is claimed is shown in solid lines in the drawings.

The broken lines showing a medical device illustrate environment, whereas the broken lines showing a display screen and elements of the graphical user interface illustrate portions of the article. None of the broken lines form part of the claimed design.
